UNITED STATES PATENT OFFICE.

FREDERICK P. ROSBACK, OF BENTON HARBOR, MICHIGAN, ASSIGNOR TO F. P. ROSBACK COMPANY, OF BENTON HARBOR, MICHIGAN.

PRINTING PRESS.

Application filed March 28, 1924. Serial No. 702,566.

To all whom it may concern:

Be it known that I, FREDERICK P. ROSBACK, a citizen of the United States, residing at Benton Harbor, county of Berrien, 5 State of Michigan, have invented certain new and useful Improvements in Printing Presses, of which the following is a specification.

This invention relates to improvements in 10 printing presses.

The main object of the invention is to provide in a printing press an improved inking means.

A further object is to provide in a printing 15 press an improved inking means whereby no ink is supplied when the "impression is off".

Further objects, and objects relating to 20 details and economies of construction, will definitely appear from the detailed description to follow.

I accomplish the objects of my invention 25 by the devices and means described in the following specification. The invention is clearly defined and pointed out in the claims.

A structure which is a preferred embodiment 30 of my invention is clearly illustrated in the accompanying drawing, forming a part of this application, in which:

Fig. I is a side elevation of a printing press embodying the features of my invention, only such parts of the machine being shown as are deemed necessary to illustrate 35 my improvements and various parts being shown by dotted lines.

Fig. II is a top plan view, the machine being shown mainly by dotted lines.

Fig. III is a fragmentary side elevation 40 mainly in dotted lines, showing means for operating or controlling the movement of the form roller frame.

Fig. IV is a fragmentary side elevation 45 showing means for holding the ductor roller out of contact with the fountain roller when the impression is "off".

Fig. V is a fragmentary plan view, showing details of the ductor roll control mechanism.

Fig. VI is a detail view partially in section 50 on a line corresponding to line 6—6 of Fig. V, showing further details of the ductor roll control means.

In the drawing similar reference charac-

ters refer to similar parts throughout the 55 several views, and the sectional views are taken looking in the direction of the little arrows at the ends of the section lines.

Referring to the drawings, 1 represents the main frame of the machine, 2 the plow and 60 3 the platen.

In Fig. I, the press is closed. In Fig. III, the press is shown open.

The plow is pivotally mounted at 4. An oscillating movement is imparted thereto by 65 the crank disc 5 and the connecting rod 6. The roller frame 7 carries the form rollers 8, the roller frame being pivoted at 9 on the plow.

In Fig. III, the form roller frame is 70 shown in its fully actuated position, that is, with the form rollers at the limit of their down stroke on the form. In Fig. I, the form rollers are shown in ink receiving position, or in contact with the inking cylinder 75 10.

The roller frame is actuated by a toggle mechanism consisting of the links 11, 12 and 13. The link 13 is pivotally connected at 14 to the arm 15 on the plow and at 19 to 80 the link 12. The link 11 is connected at 16 to the form roller frame and to the link 12 at 17, while the link 12 is pivoted to the frame of the machine at 18. The motion of the form roller frame is governed by the 85 relative length and the pivotal points of these links. It is, of course, necessary that the links in this connection be arranged so that the full stroke carries the form rollers across the form.

It will be noted that the inking cylinder 10 is mounted close to the point 20 of the plow, thereby shortening the necessary stroke of the roller frame.

Referring again to the toggle for imparting movement to the roller frame, it will be noted that the pivot point 14 for the link 13 swings about the pivot point 4 for the plow. The pivot 18 for the link 12 being a fixed point, the roller frame is rocked 100 or oscillated and, owing to the relation of the link pivots, it is actuated with a variable speed stroke, the speed decreasing and being quite slow while the form rollers are in engagement with the inking cylinder, 105 so that the form rollers are maintained in engagement therewith for a substantial period of each stroke, thus insuring that

the ink shall be well distributed to the form rollers.

Ink is supplied to the inking cylinder 10 from the fountain roller 21 driven from the pawl and ratchet mechanism 22, the pawl being connected by the link 23 to the roller frame 7. The ink is transferred to the inking cylinder 10 by means of the ductor roller 24 and the distributing rollers 25, 26, 27 10 and 28—see Fig. IV.

Movement is imparted to the ductor roller from the connecting rod 6 by means of the link 29 which passes through the arm 30 on the rock shaft 31 carrying the arms 32 by 15 which the ductor roller is carried. The link 29 is yieldingly connected to the arm 30 through the coiled springs 33 and 34 arranged on opposite sides of the arm and supported on the rod by means of the adjustable collars 35. These springs are of such tension as to normally swing the ductor roller, but yield when the ductor roller is locked in inoperative position, as will be described hereinafter. The springs also 20 compensate for any excess movement in the rod 29, that is, normally the movement of the rod exceeds that required for swinging the ductor roller.

With the parts thus connected, at each 30 stroke of the press, the ductor roll is swung into contact with the fountain roll, receiving ink therefrom, and is then swung into contact with the distributing roller 25, the ink being squeezed between the rollers 25 35 and 26, and then delivered to the inking cylinder 10. The rollers 27 and 28 assist in the even distribution of the ink by contact with the inking cylinder and with each other. The operation described is the normal operation.

However, in practice, should the feeder not be able to feed the paper sufficiently fast, or should the feed be checked, the type form would come into contact with the tympan 45 transferring an impression thereto, so that when the next sheet was placed on the platen it would receive an impression on the back from the tympan, or so-called "offset impression". To prevent this, means are provided 50 so that no impression is made although the stroke be completed. This is controlled from the lever 36 pivoted at 37 and connected by the link 38 and the arm 39 to the rock shaft 40. This rock shaft has an arm 41 connected 55 by the link 42 to an arm 43 on the eccentric 44 by means of which the connecting rod 6 is connected to the plow, so that rotation of this eccentric has the effect of changing the length of the connecting rod to such an extent that when the lever is on its rearward 60 position, no impression is made.

To prevent an excess supply of ink being delivered to the inking cylinder while the impression is "off", the parts as stated being shown in this position by full lines in

Fig. IV, I provide means for supporting the ductor roll 24 so that it does not contact with the fountain roller.

It should also be noted that when the impression is "off", the frame 7 does not travel 70 as far up as in normal operation. The end of its stroke when the impression is "off" is shown by full lines in Fig. IV and when it is "on" by dotted lines.

On the rock shaft 31 carrying the ductor 75 roll supporting arms 32 is a pin 45 adapted to engage the hole 46 in the locking bar 47 carried by the rock shaft 48 shown in detail in Fig. VI. This rock shaft has an arm 49 supported by the spring 50 on the rod 51, 80 the rod being mounted on the arm 43. The rod reciprocates through the arm 49 and has an adjustable collar 52 for supporting the spring 50. When the parts are in the position shown by full lines in Fig. IV, the locking bar is thrown downwardly into engagement with the pin 45 thereby locking the ductor roll in the position shown by full lines, so that on the next upward stroke of the rod 29 the ductor roll cannot contact 85 with the ink fountain roller 21.

A yielding locking pin or detent 54 is supported upon the frame to coact with the locking bar 47, preventing it changing its position except when the roller 53 is engaged by the frame 7 or when actuated by the spring 50. Assuming the parts in position shown by the full lines or the impression "off" and the lever 36 shifted to throw it on, the locking bar would remain in full 90 line position shown in Fig. IV until released by the engagement of the frame 7 with the roller 53. This disengages the locking bar from the pin 45, allowing the ductor roll to operate until the impression 100 is again thrown "off".

In the accompanying drawing I have illustrated only such parts of a printing machine as seem necessary to illustrate an embodiment of my invention which I have found 110 very practical. I have not attempted to illustrate and describe various modifications and adaptations which I contemplate, or modifications which might be necessary to adapt my improvements to other forms of 115 presses, as I believe the disclosure made will enable those skilled in the art to which my invention relates to embody or adapt my improvements as may be desired.

Having thus described my invention what 120 I claim as new and desire to secure by Letters Patent is:

1. The combination in a printing press including a pivotally mounted plow, of means for oscillating said plow, an inking cylinder, a form roller frame pivotally mounted on said plow, form rollers carried by said frame, means for actuating said form roller frame comprising an arm on said plow disposed above its pivot, a pair 130

of pivotally connected links, one of which is pivotally connected to said frame and the other to a fixed support, a third link pivotally connected to one of said links and to 5 said arm on said plow whereby the said roller frame is actuated with a speed decreasing on its upward stroke so that the form rollers are maintained in engagement with the inking cylinder for a substantial 10 period, and means for supplying ink to said inking cylinder.

2. The combination in a printing press including a pivotally mounted plow, of means for oscillating said plow, an inking 15 cylinder, a form roller frame pivotally mounted on said plow, form rollers carried by said frame, means for actuating said form roller frame comprising a pair of pivotally connected links, one of which is 20 pivotally connected to said form roller frame and the other to a fixed support, and a third link pivotally connected to one of said links and to said plow whereby the said roller frame is actuated with a speed 25 decreasing on its upward stroke so that the form rollers are maintained in engagement with the inking cylinder for a substantial period, and means for supplying ink to said inking cylinder.

3. The combination in a printing press including a pivotally mounted plow, of a form roller frame pivotally mounted on said plow, form rollers carried thereby, an inking cylinder, means for supplying ink 35 thereto, means for oscillating said plow, and a toggle connection for said form roller frame to said plow and to the frame of the press whereby the form roller frame is actuated with a variable speed stroke, the slow- 40 est speed being at the upper end of the stroke whereby the form rollers are maintained in contact with the inking cylinder for a substantial period.

4. The combination in a printing machine 45 including a pivotally mounted plow, of a form roller frame pivotally mounted on said plow, form rollers carried thereby, an inking cylinder, means for supplying ink thereto, means for oscillating said plow, and an 50 operating connection for said form roller frame to said plow whereby the form roller frame is actuated with a variable speed stroke, the slowest speed being at the upper end of the stroke whereby the form rollers 55 are maintained in contact with the inking cylinder for a substantial period.

5. The combination in a printing press including a pivotally mounted plow, of means for oscillating said plow comprising a crank 60 and connecting rod, said connecting rod having an adjustable connection to said plow whereby the stroke of the plow may be varied to throw the press "off" or "on", an inking cylinder, form rollers, a form roller 65 frame pivotally mounted on said plow, oper-

ating connections for said form roller frame, a fountain roller, means for transferring ink from said fountain roller to said inking cylinder comprising a ductor roll, means for oscillatingly supporting said ductor roll 70 comprising a rock shaft, an arm on said rockshaft, a push rod carried by said connecting rod and slidably arranged through said arm on said rock shaft, said push rod having springs mounted thereon to oppositely engage said arm providing a yielding connection thereto, means for locking said rockshaft in inoperative position comprising a pin on said rock shaft, a pivotally mounted locking bar adapted to engage said pin and 80 provided with a roller operatively associated with said form roller frame, a detent coacting with said locking bar for yieldingly supporting it in its adjusted positions, and a push rod carried by said connecting 85 rod adjusting means and having a yielding connection to said locking bar whereby the locking bar is actuated to pin engaging position when said connecting rod is adjusted to throw the press "off", the said locking 90 bar being released by said inking roller frame when the press is again thrown "on".

6. The combination in a printing press including a pivotally mounted plow, of means for oscillating said plow comprising 95 a crank and connecting rod, said connecting rod having an adjustable connection to said plow whereby the stroke of the plow may be varied to throw the press "off" or "on", an inking cylinder, form rollers, a form roller 100 frame pivotally mounted on said plow, operating connections for said form roller frame, a fountain roller, means for transferring ink from said fountain roller to said inking cylinder comprising a ductor roll, means for oscillatingly supporting said ductor roll comprising a rockshaft, an arm on said rockshaft, a push rod carried by 105 said connecting rod and slidably arranged through said arm on said rockshaft, said push rod having springs mounted thereon to oppositely engage said arm providing a yielding connection thereto, means for locking 110 said rockshaft in inoperative position comprising a pin on said rockshaft, a pivotally mounted locking bar adapted to engage said pin and provided with a roller operatively associated with said form roller frame, and a push rod carried by said connecting rod adjusting means and having a yielding connection to said locking bar 115 whereby the locking bar is actuated to pin engaging position when said connecting rod is adjusted to throw the press "off", the said locking bar being released by said inking roller frame when the press is again thrown "on".

7. The combination in a printing press including a pivotally mounted plow, of means for oscillating said plow comprising 120 a crank and connecting rod, said connecting rod having an adjustable connection to said plow whereby the stroke of the plow may be varied to throw the press "off" or "on", an inking cylinder, form rollers, a form roller 125 frame pivotally mounted on said plow, oper-

ating connections for said form roller frame, a fountain roller, means for transferring ink from said fountain roller to said inking cylinder comprising a ductor roll, means for oscillatingly supporting said ductor roll comprising a rockshaft, an arm on said rockshaft, a push rod carried by said connecting rod and slidably arranged through said arm on said rock shaft, said push rod having springs mounted thereon to oppositely engage said arm providing a yielding connection thereto, means for locking said rockshaft in inoperative position comprising a pin on said rock shaft, a pivotally mounted locking bar adapted to engage said pin and provided with a roller operatively associated with said form roller frame, and a push rod carried by said connecting rod adjusting means and having a yielding connection to said locking bar whereby the locking bar is actuated to pin engaging position when said connecting rod is adjusted to throw the press "off", the said locking bar being released by said inking roller frame when the press is again thrown "on".

8. A crank and connecting rod, means for adjustably connecting said connecting rod to said plow whereby the stroke of the plow may be varied to throw the press "off" or "on," an inking cylinder, form rollers, a form roller frame pivotally mounted on said plow, operating connections for said form roller frame, a fountain roller, means for transferring ink from said fountain roller to said inking cylinder comprising a ductor roll, means for oscillatingly supporting said ductor roll comprising a rockshaft, an arm on said rockshaft, a push rod carried by said connecting rod and slidably arranged through said arm on said rockshaft, said push rod having springs mounted thereon to oppositely engage said arm providing a yielding connection thereto, means for locking said ductor roll in inoperative position operatively connected to said connecting rod adjusting means whereby the ductor roll is rendered inoperative when the connecting rod is adjusted to throw the press "off," and means for releasing said ductor roll locking means actuated by said inking roller frame when the press is "on."
9. The combination in a printing press including a pivotally mounted plow, of means for actuating said plow, a throw-off means for said plow, an inking cylinder, form rollers, a form roller frame pivotally mounted on said plow, operating connections for said form roller frame and plow, a fountain roller, means for transferring ink from said fountain roller to said inking cylinder comprising an oscillatingly mounted ductor roll, means for oscillating said ductor roll operatively associated with said plow actuating means, means for locking said ductor roll to inoperative position operatively associated with said throw-off means whereby the ductor roll is locked in inoperative position when the press is "off," and means for disengaging said locking means including said inking roller frame whereby the ductor roller is released when the press is "on."
10. The combination in a printing press including a pivotally mounted plow, of means for actuating said plow, a throw-off means for said plow, an inking cylinder, form rollers, a form roller frame pivotally mounted on said plow, operating connections for said form roller frame and plow, a fountain roller, means for transferring ink from said fountain roller to said inking cylinder comprising an oscillatingly mounted ductor roll, means for oscillating said ductor roll operatively associated with said plow actuating means, means for locking said ductor roll to inoperative position operatively associated with said throw-off means whereby the ductor roll is locked in inoperative position when the press is "off," and means for disengaging said locking means including said inking roller frame whereby the ductor roller is released when the press is "on."
- In witness whereof, I have hereunto set my hand.

FREDERICK P. ROSBACK. [L. s.]
